UNITED STATES PATENT OFFICE.

HARRY DEL MAR, OF NEW YORK, N. Y., ASSIGNOR TO BOILERS AND ENGINEERING COMPANY, OF JERSEY CITY, NEW JERSEY, A CORPORATION OF NEW JERSEY.

WATER-TUBE BOILER.

No. 822,885.

Specification of Letters Patent.

Patented June 5, 1906.

Application filed November 29, 1905. Serial No. 289,548.

To all whom it may concern:

Be it known that I, HARRY DEL MAR, of the city, county, and State of New York, have invented a new and useful Improvement 5 in Water-Tube Boilers, of which the following is a full, clear, and exact description.

This invention relates to improvements in water-tube boilers, and particularly to that class of boilers that consists of series of vertically-arranged rows of tubes, adjacent series 10 being at an angle to each other and oppositely inclined between sets of headers that form the sides of the boiler.

The object of the invention is to provide 15 the headers with openings for the tubes so as to arrange the tubes in a staggered way, and the headers are arranged to face one another diagonally—that is, an upper header on one side faces the corresponding header on the lower tier of the other side.

Another object of the invention is to utilize 20 the space immediately above the lower part of a series of tubes running from header to header by inserting a set of tubes to establish communication between the upper 25 header and the steam-drum.

This boiler also provides a feed-drum on each end of each series of headers to receive the return from the steam-drum and distribute it to the headers.

With these ends in view my invention consists of certain combinations that will be hereinafter described and finally embodied in the clauses of the claim.

Reference is to be had to the accompanying drawings, forming a part of this specification, in which similar figures of reference indicate corresponding parts in all the views.

Figure 1 is a side view of the boiler with the 40 steam-drum and mud-drums in section. Fig. 2 is a partial view in section of the boiler on line 2 2 in Fig. 1. Fig. 3 is a plan of the boiler with a part of the steam-drum removed; and Fig. 4 is a section of the tubes of 45 one of the headers, showing the header in elevation.

In the drawings, 10 is the usual steam-drum, connected by the pipes 11 with the tops of the headers 12. These headers are 50 arranged as shown particularly in Figs. 2 and 3, being staggered by the distance between two rows of tubes, thus bringing the headers of an upper tier exactly facing the header of

the lower tier on the opposite sides. The tubes 13 are arranged in rows and run diagonally across from header to header. The upper headers in the space left between the downwardly-sloping tubes running to the lower headers are connected by the tubes 14 with the steam-drum. 55

Each lower header on the front of the boiler is provided with tube-openings for the tubes 15, which communicate with the headers on the back end, which are longer. This provides a set of tubes approaching the grate 60 on the back end and receiving the full benefit of the fire. The feed-headers 16 at the four corners of the boiler are fed by the pipes 17 from the steam-drum and return the cooler water to the headers 12 by means of the mud-drum 18 and the pipes 19. The opposed feed-drums are connected by the equalizing-pipes 20 to create an even distribution of water. The headers are provided on their outer 65 faces with openings 21, having caps, the openings affording entrance for expanding tubes, 70 cleaners, and the like.

In Fig. 4 I show the arrangement of the tubes in each header. They are arranged so as not to afford a straight path for the heat in 80 a vertical direction. They overlap a little to cause the heat to follow a path indicated by the arrow in Fig. 4.

It will be obvious that the boiler on these lines will be an economical and simple boiler. 85 It will also be seen that by using headers having the three rows of tubes to a header instead of the ordinary arrangement with one row of tubes to a header I not only get the staggered effect of the tubes, but a row of 90 tubes will come where a joint would appear if the ordinary headers having one row of tubes were used. Thus I get additional heating space and simpler construction.

Having thus fully described my invention, 95 I claim as new and desire to secure by Letters Patent—

1. A boiler consisting of a steam-drum, tiers of headers connected with the steam-drum and arranged diagonally opposite and side by side, rows of diagonally-arranged tubes connecting each header with the diagonally-opposed header, and rows of tubes arranged to connect the lower front headers with the lower rear headers between the first- 105 mentioned rows of tubes.

2. A boiler comprising a steam-drum, tiers of oppositely-arranged headers, two sets of tubes extending from each upper header to the diagonally-opposed lower header, a row of tubes arranged to connect each upper header with the steam-drum and arranged between the first-mentioned sets of tubes, and a row of tubes connecting each lower header on one side with the lower header on the other side and also placed between the diagonally-arranged sets of tubes.

3. A water-tube steam-boiler comprising a steam-drum, tiers of headers arranged diag-

nally opposite and side by side, rows of diagonally-arranged tubes connecting each header with the diagonally-opposed header, mud-drums, connections between the lower headers and the mud-drums, and rows of tubes connecting the headers on opposite sides of the steam-drum with the said steam-drum, the said rows of tubes being arranged between the rows connecting the headers.

HARRY DEL MAR.
